UNITED STATES PATENT OFFICE.

GEORGE A. GOODSON, OF MINNEAPOLIS, MINNESOTA.

ELECTRIC IGNITER FOR EXPLOSIVE-ENGINES.

No. 904,196.

Specification of Letters Patent.

Patented Nov. 17, 1908.

Application filed February 8, 1902. Serial No. 93,136.

To all whom it may concern:

Be it known that I, GEORGE ARTHUR GOODSON, a citizen of Dominion of Canada, residing at Minneapolis, in the county of Hennepin and State of Minnesota, have invented certain new and useful Improvements in Electric Igniters for Explosive-Engines; and I do hereby declare the following to be a full, clear, and exact description of the invention, such as will enable others skilled in the art to which it appertains to make and use the same.

My invention has for its object to provide an improved electric igniter for explosive engines; and to this end, it consists of the novel devices and combinations of devices hereinafter described and defined in the claims.

My invention is illustrated in the accompanying drawings as applied to a two cycle explosive engine, and the generator shown is substantially the same as that disclosed in my U. S. Patent 734,851, granted to me of date July 8, 1903, on my application S. N. 86,009, filed Dec. 16, 1901.

In the said drawings, wherein like notations refer to like parts throughout the several views, Figure 1 is an end elevation of the engine with my invention embodied therein, some parts being broken away, and others shown in section. Fig. 2 is a side elevation of the same, with some portions broken away. Fig. 3 is a cross section through the sparking device, and a portion 35 of the engine cylinder in the same plane as shown in Fig. 1, but on a larger scale. Fig. 4 is a horizontal section on the line $x^4 x^5$ of Fig. 3. Fig. 5 is a bottom plan view of the sparking plug detached. Fig. 6 is a detail of the generator on the line $x^6 x^7$ of Fig. 1. Fig. 7 is a view chiefly in vertical section, showing a modified form of the sparkler detached. Fig. 8 is a plan view of the same; and Fig. 9 is a detail showing the armature contact or electrode of Fig. 9, in plan view detached.

The engine being of the well known two cycle type, it is, of course, not necessary to detail the structure thereof. It is sufficient, for the purposes of this case, to note the cylinder casting 1 and the crank shaft 2. For holding the elements of my sparkler, I employ a screw plug 3 adapted to be seated in one wall of the explosion chamber of the engine, which plug may be of the form shown in Figs. 1 and 3, or of the form

shown in Fig. 7. In the plug 3 are mounted the circuit breaking electrodes which may be of the form marked 4 and 5 respectively, as shown in Figs. 1 to 5 inclusive, or of the form marked 4^4 and 5^5 as shown in Figs. 7 to 9 inclusive. In each form the fixed electrode is held in a suitable insulating bushing 6 secured in the plug 3. In each form, the movable member of the electrodes is in the nature of an armature. As shown in the main views, Figs. 1 to 5 inclusive, the armature is in the form of a bell-crank lever 5, the short arm of which is subject to the pole pieces of the double magnet 7 anchored to the head or outside portion of the plug 3, with its pole pieces extending therethrough into close proximity to the short arm of said lever 5. The magnet 7, and the fixed electrode 4, are connected into the igniter circuit by wire 8, detachable at the binding post 9, and leading directly from the source of supply. The armature lever 5, constituting the other electrode, is not insulated, but is directly connected with one wall of the brass plug 3 at the hinged joint thereof, and may also be connected by a coiled wire 10, to insure perfect contact between the said parts. The wire 10, if made of a kind of metal that will stand the heat incidental to its position, may also act as a spring for holding the armature electrode 5 in its closed position. The other lead wire from the current source is assumed to tap the engine castings whence the current reaches the screw plug 3, and through the same the armature contact 5. The magnet 7 is protected by a suitable cap or housing 11. The plug 3 is recessed to afford clearance for the proper motion of the armature lever 5.

In the modification shown in Figs. 7, 8 and 9, the movable member of the circuit breaking electrode is in the form of a piston armature 5^5 mounted for straight line reciprocating motion within the brass plug 3. The fixed electrode 4^4 , in this modification, is of proper form to bring its contact point directly under the contact point of the armature 5^5 . The armature 5^5 assumes its circuit closing position under the action of gravity; and to better insure this result, it has a loose fit in its seat and may be provided with longitudinal grooves throughout its entire length on its peripheral surface to afford free passage for the gases from the explosion.

chamber of the engine, thereby making both ends thereof subject to the same pressure or be balanced.

Referring now to the generator, I employ a magneto A having applied to its armature an impelling device adapted to be tripped into action intermittently by the engine, for instantaneously imparting motion to the armature at the proper speed to generate the required current, regardless of the speed of the engine. One form of such a generator is illustrated in Figs. 1, 2 and 6. The engine shaft 2 has fixed thereto, with freedom for angular adjustment thereon, a gear wheel 12 which engages a gear wheel 13 of the same size which is loosely mounted on the armature shaft of the magneto. Alongside the gear 13 is a disk 14 fixed to the armature shaft and provided with a crank *b* extending therethrough. The loose wheel 13 has a lateral stud on its outer face for coöperation with the inner end of the pin *b* of the disk 14. The crank pin *b* is connected by a stiff coiled spring 15 to an anchor bracket 16 shown as secured to the permanent magnets in the magneto. The spring 15 is applied under tension, and tends to hold the crank pin *b* of the disk 14 at its highest point, or as near as possible to the anchored end of the spring; and when the spring is in this, its normal position, its axis is on a line which, if produced, would cross the axis of the armature shaft. Under the rotation of the engine shaft 2, the gear 12 fixed thereto will turn the loose gear 13 on the armature shaft; and when the cam lug *a* of the loose gear 13 comes in contact with the inner end of the crank pin *b* on the disk 14 fixed to the armature shaft, the latter will be turned with the loose gear 13 for a little more than one-half a revolution, to-wit, until the spring 15 has been carried to the forward side of the armature shaft, in respect to the motion of rotation; and, when this occurs, the spring 15, by the half turn of the disk having been set under increased tension, will suddenly throw the disk forward in advance of the loose gear, and thereby impart a corresponding quick throw to the armature of the magneto at a speed sufficient to generate the required current, regardless of the speed of the engine; and, of course, when the spring has drawn the crank pin *b* to its highest position, it will there stop the disk 14 and the armature shaft where these parts remain idle until the next half revolution of the loose gear has been completed. The parts of this impelling device are so positioned, relative to each other, and relative to the crank shaft of the engine, that the impelling device will be tripped into action at exactly the right instant, in respect to the motion of the engine piston, for securing the spark at the instant of highest E. M. F.

65 One terminal of the armature winding of

the magneto is soldered, or otherwise made fast in contact with the armature shaft, whence the current may pass through the metallic parts of the generator and the engine castings to the screw plug of the spark, and therefrom to the movable or armature member of the circuit breaking electrode. The other terminal of the magneto armature winding is suitably insulated, and contact therewith is made through an insulated brush 17 connected with the wire 8 leading to the magnet 7, and through the same to the fixed electrode of the spark.

Having regard to the spark, as shown in Figs. 1 to 5 inclusive, gravity and the spring 10 coöperate to hold the armature lever 5 away from the cores of the magnet 7, and the two electrodes in their closed position; and this force is such, in respect to the size of the cores and windings of the magnet 7, that the armature lever 5 will be moved into its reverse or closed position with respect to the magnet, and the electrodes thereby be separated at a predetermined voltage which is attained only substantially at the instant of maximum current generation by the generator. The same remark applies to the form of plug shown in Figs. 7, 8 and 9, with the exception that gravity alone holds the piston armature, there shown, away from the core of the magnet and the electrodes in their closed position. The coiled wire, there shown as encircling a part of the piston armature 5^a and connecting the same with the plug 3, is primarily intended to insure a good conductor for the current.

I prefer the form of spark, as shown in Figs. 1 to 5, for the reason that the pole pieces of the magnet may be closer to the armature lever 5 when the latter is in circuit closing position and nevertheless afford provision for a long opening movement between the circuit breaking electrodes. This makes the circuit breaking action somewhat quicker and more positive than with the form shown in Figs. 7 to 9.

In practice, fire proof magnets may be employed, and the parts which project into the explosion chamber be made of proper material to withstand the heat. While the sparking plug, herein disclosed, has the special features of advantages herein described, it must, of course, be understood, that so far as the general combination or broad feature of the invention herein disclosed and claimed, to-wit, the intermittently acting magneto combined with a magnetic plug or motor controlled sparking device, as defined in claim 1, is concerned, the magnetic plug or sparking device might be of any suitable construction.

In the generator shown and described, the movable member thereof is rotary, and the intermittently acting impelling device always operates to turn the rotary member of

the generator in the same direction; and this structure and mode of operation has important advantages, all as set forth in my foundation Patent 734,851, of July 28th, 1903; but for the purpose of certain features of the present case, the movable member of the generator might vibrate instead of rotate, or, in other words, the generator might be of the form disclosed and claimed in my Patent 10 725,644 of April 14th, 1903.

Extensive usage has demonstrated the efficiency of the invention herein disclosed and claimed, for the purposes had in view.

What I claim is:

- 15 1. In an explosive engine, the combination with an electric generator having a rotary member, of intermittently acting means turning said member always in the same direction and at a speed which is independent 20 of the speed of the engine, a device actuated by the engine for tripping said means into action, an igniter circuit supplied from said generator and provided with electrodes in the explosion chamber, one of which is movable, and an electric motor also in said circuit and controlling the movable electrode to

make and break the circuit at the proper time, substantially as described.

2. In an explosive engine, the combination with a magneto generator arranged to 30 generate, intermittently, current for the spark, an igniter circuit supplied from said generator, and a sparking plug secured in one wall of the explosion chamber of the engine and provided with a pair of electrodes 35 projecting into said explosion chamber, insulated from each other, one thereof being stationary and the other carried by a hinged bell-crank armature lever, an electro magnet on the exterior of said plug having a core or 40 cores which extend to the inside of the plug in position for action on said armature lever, and which electrodes and which magnet are connected into the igniter circuit, all for co-operation, substantially as described. 45

In testimony whereof, I affix my signature in presence of two witnesses.

GEORGE A. GOODSON.
